US0D1070960S

(12) **United States Design Patent** (10) **Patent No.:** **US D1,070,960 S**
(45) **Date of Patent:** **** Apr. 15, 2025**

(54) **GLASSES**

(71) Applicant: **LUXOTTICA S.R.L.**, Agordo (IT)
(72) Inventors: **Matteo Cesare Battiston**, Milan (IT);
Fabio Verdelli, Milan (IT)
(73) Assignee: **LUXOTTICA S.R.L.**, Agordo (IT)

(**) Term: **15 Years**

(21) Appl. No.: **29/907,675**

(22) Filed: **Jan. 8, 2024**

Related U.S. Application Data

(62) Division of application No. 29/806,871, filed on Sep. 7, 2021, now Pat. No. Des. 1,050,237.

(57) **CLAIM**

The ornamental design for glasses, as shown and described.

DESCRIPTION

FIG. 1 is a perspective view of a glasses showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a rear perspective view thereof; and,

FIG. 8 is a right side elevational view thereof.

The broken lines represent portions of the glasses and form no part of the claimed design.

1 Claim, 6 Drawing Sheets
